UNITED STATES PATENT OFFICE.

FRANK T. MALÍČH, OF WADSWORTH, OHIO.

SHOE-CLOSURE FASTENER.

Application filed February 21, 1924. Serial No. 694,259.

To all whom it may concern:

Be it known that I, FRANK T. MALÍČH, a citizen of Yugoslavia, residing at Wadsworth, in the county of Medina and State 5 of Ohio, have invented certain new and useful Improvements in Shoe-Closure Fasteners, of which the following is a specification.

This invention relates to certain new and useful improvements in shoe closure fasteners wherein the forward meeting edges of 10 the shoe upper are moved into overlapping relation and so retained by link devices.

The primary object of the invention is to provide a shoe closure fastener embodying a plurality of separate link members carried by one edge of the shoe upper while the opposite edge of the shoe upper is provided with a pair of spaced openings through which the link members are 15 extended with the link members interlocked with each other to form a closure for the shoe upper.

With the above and other objects in view that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views.

Figure 8 shows side and edge elevational views of the upper link with which the locking link is associated, and

Figure 9 shows side and edge elevational views of one of the remaining group of links.

Referring more in detail to the accompanying drawing, there is illustrated a shoe upper wherein the meeting edges 1 and 2 thereof overlie each other as illustrated in Fig. 4, the fastening devices being permanently carried by the underlying section 1 and adapted to be individually passed through slotted openings 3 in the outer overlying section 2 for interlocking engagement with each other outwardly thereof.

The fastening devices are in the form of a plurality of independent link members supported by pins of eye formation, the 75 loop eyes 4 being carried by a shank 5 that has a button 6 upon the other end thereof, the eye shanks 5 passing through spaced vertically aligned openings 7 in the underlying upper section 1 and permanently retained therein by the strip 8 overlying the buttons 6 and stitched along its edges to the adjacent face of the upper section 1, this construction being clearly illustrated in Fig. 4.

A plurality of links 9 of the form best illustrated in Fig. 9, the same being of tapering formation and having a relatively wide

Fig. 9 and having an opening 20 in one end thereof to receive an eye 4 while the body of the link 19 is provided with a longitudinally extending slotted opening 21 that is traversed by a cross slot 22, the outer wall of which is centrally notched as at 23 and further provided with inwardly extending lugs 24.

When all of the link members 9, 15 and 19 have been projected through the slotted openings in the overlying section 2 of the shoe upper, the lowermost link has the superposed one extended through the opening 10 thereof with the eye 4 supporting the upper links also projecting through said link openings. The several links are interengaged with each other in this manner and as illustrated in Fig. 1 with the link 19 extended through the opening in the uppermost link of the type illustrated in Fig. 9. The locking link 15 is then shifted to the position shown in Fig. 2 to align the major transverse axis thereof with the longitudinal slotted opening 21 in the link 19 and during which time the rectangular eye 12 is disposed for free passage through the cross slot 22 in the link 19. When the locking link 15 and eye 12 have been completely projected through the link 19, the eye 12 is moved to dispose one side edge of the eye 12 in the central notch 23 of the link 19 with the lugs 24 engaging the adjacent sides of the eye. The locking link 15 is then permitted to drop to the vertical position as illustrated in Fig. 1, due to the cutaway portion 17 forming a clearance with respect to the side walls of the eye 12 for such movement and as the locking link 15 is solid and slightly weighted, the same will always assume a depending or hanging position as illustrated to insure the proper locking of the several link members and the retention of the upper sections 1 and 2 of the shoe in closed position.

While there is herein shown and described the preferred embodiment of the present invention it is nevertheless to be understood that minor changes may be made therein without departing from the spirit and scope of the invention as claimed.

50 What is claimed as new is:—

1. In a closure fastener for shoe uppers, a plurality of links carried by one side of the shoe upper, the other side of the shoe upper having slits therein through which

the links are projected with the links interlocked with each other outwardly of the slits, the two upper links constituting locking members for the series of interlocked links. 65

2. In a closure fastener for shoe uppers, a plurality of links carried by one side of the shoe upper adapted for projection through the other side of the upper for interlocking connection with each other, a locking link for retaining the links in interlocked condition located at the upper end of the series of links, and eye-members supporting the links capable of rotary movement in the shoe upper. 60

3. In a closure fastener for shoe uppers, a plurality of links carried by one side of the shoe upper, the other side of the shoe upper having slits therein through which the links are projected with the links interlocked with each other outwardly of the slits, the two upper links constituting locking members for the series of interlocked links, and eye members supporting the links capable of rotary movement in the shoe upper. 70

4. In a closure fastener for shoe uppers, a plurality of links carried by one side of the shoe upper adapted for projection through the other side of the upper for interlocking connection with each other, a locking link for retaining the links in interlocked condition located at the upper end of the series of links, eye-members supporting the links capable of rotary movement in the shoe upper, the link adjacent the upper link having crossed slots therein and the upper link projected through the longitudinal slot of the adjacent link and subsequently twisted out of alignment with the longitudinal slot. 80

5. In a closure fastener for shoe uppers, a plurality of links carried by one side of the shoe upper, the other side of the shoe upper having slits therein through which the links are projected with the links interlocked with each other outwardly of the slits, the link adjacent the upper link having crossed slots therein and the upper link projected through the longitudinal slot of the adjacent link and subsequently twisted out of alignment with the longitudinal slot, and eye members supporting the links capable of rotary movement in the shoe upper. 90

In testimony whereof I affix my signature.

FRANK T. MALICH.
